CORE CATCHER

Donald Mackenzie and John E. Hoffoss, Houston,
Tex., assignors to Reed Roller Bit Company,
Houston, Tex., a corporation of Texas

Application January 7, 1938, Serial No. 183,788

8 Claims. (Cl. 255—72)

This invention relates in general to core drills for use in taking samples of the formation during the drilling of a well or the like, and more particularly has reference to a device commonly known as a core catcher, which device is located adjacent the lower end of the barrel for receiving the core, and is for the purpose of breaking the core off, and for holding the core and preventing it from dropping out through the bottom of the core barrel during the time that the core barrel is being drawn up to the top of the well.

It is an object of this invention to provide a core catcher which shall be of simple construction and efficient in operation.

More specifically it is an object of this invention to provide a core catcher which will be less expensive to manufacture than previous core catchers, and which will be unfailing in its operation.

One other object of this invention is to provide a core catcher composed of a relatively small number of component parts requiring the least possible amount of labor to produce and assemble.

Another object of this invention is to provide a core catcher which will be extremely durable and require a minimum of repair and attention.

Another object is to provide a core catcher which when it requires repairs may be repaired with the least possible expenditure of labor and material.

One other object is to provide a core catcher which will present a smooth internal bore so as to permit the core to enter and pass freely therethrough.

Other objects and advantages of this invention will become apparent from the following description taken in connection with the accompanying drawing, wherein one embodiment of this invention is illustrated. It is to be understood that this embodiment and illustration is not by way of limitation, but by way of explanation and illustration, and that this invention is limited in its scope only by the prior art and by the terms of the appended claims.

In the drawing:

Fig. 1 is a vertical cross sectional view illustrating a core catcher constructed in accordance with this invention, and showing its relation to a core bit when in use therein.

Fig. 2 is a horizontal cross section taken along the line 2—2 of Fig. 1.

Fig. 3 is a vertical cross section through the core catcher body showing the bearing sockets for receiving the core catcher finger bearing pins.

Fig. 4 is a vertical cross section take along the line 4—4 of Fig. 2.

The core catcher illustrated in Fig. 1 is shown as being located within the lower end of the core barrel 1 and held in place therein by means of a shoulder in the lower end of the core bit 2.

The principal part of the core catcher illustrated comprises the body 3 which is formed with a plurality of slots therein extending from its lower end upwardly as illustrated at 4. Within these slots 4 there are disposed core catcher fingers 5 and 6, these fingers being rotatively mounted upon bearing pintles 7 integral with the fingers 5 and 6 and extending in opposite directions therefrom. The pintles 7 are formed with frustoconical end portion. The pintles 7 are pivotally mounted in grooves 9 formed in the lower edge of the body 3 and extending in opposite directions from each of the slots 4.

Each of the fingers 5 and 6 is formed with a notch 10 midway of its base between the pintles 7 for the purpose of receiving a coil spring 11. One end of this spring extends lengthwise of the pin through an opening therein as indicated at 12 and the opposite end 13 extends into an opening in the inwardly extending flange 14 on the lower end of the retaining collar 15. The retaining collar 15 serves, when in position on the body 3, to hold the pintles 7 in place in the grooves 9 and thus retain the core catcher fingers 5 and 6 in position, in addition to serving as an anchor for one end of each of the finger actuating springs 10, and is secured in place on the body 3 by a plurality of circumferentially spaced rivets 16 or the like.

It will be understood from the foregoing that in the course of taking the core with a core drill equipped with the core catcher described, the core drill will be rotated in the ordinary manner to cut the core, and the core after it is out will pass upwardly between the core catcher elements 5 and 6 moving them upwardly against the tension of the springs 11.

When the core has reached the length desired, the cutting of the core will cease and the core barrel, including the core catcher, will be moved upwardly. This will cause the core catcher elements 5 and 6 to swing inwardly and separate the core from the formation at its lower end, and thereafter retain the core within the core barrel. The fingers 5 and 6 will, of course, be caused to move inwardly when the core barrel is pulled up because of the tension of the springs 11.

It is to be noted that in the construction illustrated, there is provided a structure having a sub-

stantially smooth internal bore which will offer practically no resistance to the passage of a core therethrough in an upward direction. This is because the elements 5 and 6 are mounted within the slots 4, and when in their up position their inner surfaces are substantially flush with the inner walls of the body member 3.

The construction is also extremely simple in that the fingers and their pivots are integral and 10 are all secured in place by a single retaining element, which also serves as an anchor for all the springs which urge the catcher fingers to operative position. The springs are mounted in a position where they will be best protected from 15 the action of slush, etc., and yet efficiently perform their intended function.

The design of the parts also is such as to render them easy to machine, the grooves 9 extending entirely across a segment of the end of the member 3, and the machining of the bearing pintles being a simple lathe operation. Ease of assembly is also noteworthy, the only step which cannot be performed without tools being the riveting at 16.

25 In view of the foregoing, it will be seen that a means has been provided for accomplishing all of the objects sought by this invention.

We claim:

1. In a core catcher assembly, a ring shaped 30 body member having one of its ends notched at circumferentially spaced points and grooves in the face of said end at right angles to and extending on opposite sides of each of said notches respectively, a plurality of core catcher fingers 35 mounted in said notches respectively, and having integral bearing pintles lying in said grooves on opposite sides of said notches to pivotally mount said fingers, each of said fingers being notched between said pintles and having a relatively small bore extending longitudinally of said finger from said notch, a coil spring within each such notch and having one end thereof anchored within said bore, a retaining ring fitting about said body member and having at one end an inwardly extending flange in engagement with the end of 45 said body member to retain said pintles in said grooves, said flange having bores therein receiving and anchoring the opposite ends of said springs, said springs when so anchored tending 50 to force said fingers downwardly and inwardly, and means for securing said retaining ring in place on said body.

2. In a core catcher assembly, a ring shaped 55 body member having one of its ends notched at circumferentially spaced points and grooves in the face of said end at right angles to and extending on opposite sides of each of said notches, respectively, a plurality of core catcher fingers 60 mounted in said notches, respectively, and having integral bearing pintles lying in said grooves on opposite sides of said notches to pivotally mount said fingers, and means to retain said pintles in said grooves.

3. In a core catcher assembly, a ring shaped 65 body member having one of its ends notched at

circumferentially spaced points and grooves in the face of said end, a plurality of core catcher fingers mounted in said notches, respectively, and having bearing pintles lying in said grooves to pivotally mount said finger, each of said fingers having a notch intercepting the axis of said pintles, a spring element within each of said notches for urging said fingers downwardly and inwardly about the axis of said pintles, and means for retaining said pintles in said grooves and anchoring said spring elements. 5

4. In a core catcher assembly, a ring shaped body member having circumferentially spaced openings, therein, a plurality of core catcher fingers pivotally mounted in said openings, respectively, each of said fingers having a notch therein intercepting the axis of its pivotal mounting, and a spring element within each of said notches having one end fitting snugly into an opening in the finger and the opposite end fitting snugly into an opening in said body member, said springs being tensioned to urge said fingers inwardly and downwardly with respect to said body member. 10

5. In a core catcher finger, an elongated blade, 25 and a pair of aligned oppositely extending pintles integral with said blade adjacent one end thereof, said finger having an open notch intermediate said pintles and a spring mounted in said notch and adapted to urge said blade to rotate about 30 said pintles as an axis.

6. In a core catcher assembly, a ring shaped body member having one of its ends notched at circumferentially spaced points and having grooves in the face of said end at right angles 35 to and extending on opposite sides of each of said notches, respectively, a plurality of core catcher fingers mounted in said notches, respectively, and having bearing pintles lying in said grooves on opposite sides of said notches to pivotally mount said fingers, and means to retain 40 said pintles in said grooves.

7. In a core catcher assembly, a ring shaped body member having recesses opening through its inner wall adjacent one end thereof, aligned 45 grooves in the face of said end extending on opposite sides of each of said recesses, respectively, a plurality of core catcher fingers mounted in said recesses, respectively, bearing means lying in said grooves and pivotally supporting said 50 fingers, and means to retain said bearing means in said grooves.

8. In a core catcher assembly, a ring shaped body member having recesses opening through its inner wall adjacent one end thereof, bearing recesses in the face of said end intersecting said first mentioned recesses, respectively, a plurality of core catcher fingers mounted in said recesses, respectively, bearing means lying in said bearing recesses and pivotally supporting said fingers, and means to retain said bearing means in said bearing recesses. 55

DONALD MACKENZIE,
JOHN E. HOFFOSS.
